(57) **CLAIM**

The golf ball cleaning device, as illustrated and described.

DESCRIPTION

FIG. 1 is a front elevational view of a golf ball cleaning device incorporating the design of the present invention; FIG. 2 is a rear elevational view of the golf ball cleaning device of FIG. 1;

FIG. 3 is a bottom view of the golf ball cleaning device of FIG. 1;

FIG. 4 is a top view of the golf ball cleaning device of FIG. 1;

FIG. 5 is a side elevational view of the golf ball cleaning device of FIG. 1. The opposite side is a mirror-image of the side illustrated in FIG. 5;

FIG. 6 is an elevational view of the front of the golf ball cleaning device of FIG. 1 with a towel portion attached;

FIG. 7 is a rear elevational view of the golf ball cleaning device of FIG. 6;

FIG. 8 is a bottom view of the golf ball cleaning device of FIG. 6;

FIG. 9 is a top view of the golf ball cleaning device of FIG. 6;

FIG. 10 is a side elevational view of the golf ball cleaning device of FIG. 6. The opposite side is the mirror-image of the side illustrated in FIG. 10;

FIG. 11 is a front elevational view of the golf ball cleaning device of FIG. 6 with a fastener attached to the rear of the device;

FIG. 12 is a rear elevational view of the golf ball cleaning device of FIG. 11;

FIG. 13 is a bottom view of the golf ball cleaning device of FIG. 11;

FIG. 14 is a top view of the golf ball cleaning device of FIG. 11; and,

FIG. 15 is a side elevational view of the golf ball cleaning device of FIG. 11. The opposite side is the mirror-image of the side illustrated in FIG. 15.
